UNITED STATES PATENT OFFICE.

STEWART P. FOLTZ, OF NEW CASTLE, PENNSYLVANIA, ASSIGNOR TO HARRY H.
WEINBERGER, OF NEW YORK, N. Y.

DESIGN FOR A COIN OR TOKEN.

60,018.

Specification for Design.

Patented Dec. 20, 1921.

Application filed August 31, 1921. Serial No. 497,387. Term of patent 14 years.

To all whom it may concern:

Be it known that I, STEWART P. FOLTZ, a citizen of the United States of America, residing at New Castle, in the county of Lawrence and State of Pennsylvania, have invented a new, original, and ornamental Design for Coins or Tokens, of which the following is a specification, reference being had to the accompanying drawing, forming part thereof.

Figure 1 is a view of the obverse face of the coin or token; and

Fig. 2 is a view of the reverse face thereof.

I claim:

The ornamental design for a coin or token, as shown.

In witness whereof, I have hereunto set my hand.

STEWART P. FOLTZ.
